US00D408915S

United States Patent [19]

Ogiwara

[11] Patent Number: Des. 408,915

[45] Date of Patent: **Apr. 27, 1999

[54] SCANNER FOR A DIAGNOSTIC MACHINE
USING A MAGNETIC RESONANCE
TOMOGRAPHY

[75] Inventor: **Susumu Ogiwara**, Ohtawara, Japan

[73] Assignee: **Kabushiki Kaisha Toshiba**, Kawasaki,
Japan

[**] Term: **14 Years**

[21] Appl. No.: **29/079,750**

[22] Filed: **Nov. 7, 1997**

[30] Foreign Application Priority Data

May 8, 1997 [JP] Japan 9-53715

[51] LOC (6) Cl. **24-01**

[52] U.S. Cl. **D24/158**

[58] Field of Search D24/158, 159;
378/4, 21-27; 250/363.01, 363.02, 363.04,
363.05, 363.08

[57] CLAIM

The ornamental design for scanner for a diagnostic machine
using a magnetic resonance tomography, as shown.

DESCRIPTION

FIG. 1 is a front, top and right side perspective view of
scanner for a diagnostic machine using a magnetic reso-
nance tomography, showing my new design;

FIG. 2 is a front elevational view thereof;

FIG. 3 is a right side elevational view thereof; the opposite
side being identical thereof;

FIG. 4 is a top plan view thereof; and,

FIG. 5 is a bottom plan view thereof.
